(57) **CLAIM**

The ornamental design for a window cover for automobile or replica thereof, as shown and described.

DESCRIPTION

FIG. 1 is a front, right perspective view of a window cover for automobile or replica thereof;

FIG. 2 is a rear, right perspective view of FIG. 1;

FIG. 3 is a right side elevation view of FIG. 1;

FIG. 4 is a left side elevation view of FIG. 1;

FIG. 5 is a rear elevation view of FIG. 1; and,

FIG. 6 is a top plan view of FIG. 1.

The evenly spaced broken lines in the drawings illustrate environmental features or portions of the window cover for automobile or replica thereof that form no part of the claimed design.

1 Claim, 6 Drawing Sheets
